[57] CLAIM

The ornamental design for a crocheted football helmet cap, substantially as shown and described.

DESCRIPTION

FIG. 1 is a front elevational view of a crocheted football helmet cap showing my new design;

FIG. 2 is a side elevational view, the opposite side being a mirror image thereof;

FIG. 3 is a rear elevational view thereof;

FIG. 4 is a top plan view thereof;

FIG. 5 is a bottom plan view thereof; and

FIG. 6 is a side elevational view with the chin guard in an alternate position of use.

Fig. 1.
